US00D906838S

(12) **United States Design Patent** (10) Patent No.: **US D906,838 S**
(45) Date of Patent: ** Jan. 5, 2021

(54) **PACKAGING WITH CASE FOR ELECTRONIC DEVICE**

(71) Applicant: **Apple Inc.**, Cupertino, CA (US)

(72) Inventors: **Megan J. Burmeister**, Manhattan Beach, CA (US); **Vijay Karthik Koneru**, Los Angeles, CA (US); **Christopher Wiita**, West Hollywood, CA (US); **Duy P. Le**, Los Angeles, CA (US); **Hamish Thain**, New York, NY (US); **Bart Jansen**, Brooklyn, NY (US); **Michael Rodriguez**, Brooklyn, NY (US); **Christopher Kuh**, San Francisco, CA (US); **Guillaume Raoult**, San Francisco, CA (US); **Elvin Chu**, San Francisco, CA (US); **Martin Gschwandtl**, San Francisco, CA (US); **Robert Brunner**, Glen Ellen, CA (US)

(73) Assignee: **Apple Inc.**, Cupertino, CA (US)

(**) Term: **15 Years**

(21) Appl. No.: **29/686,209**

(22) Filed: **Apr. 2, 2019**

(51) LOC (13) Cl. **09-01**

(52) U.S. Cl.

USPC **D9/721; D9/737**

(57)

CLAIM

The ornamental design for packaging with case for electronic device, as shown and described.

DESCRIPTION

FIG. 1 is a top front perspective view of packaging with case for electronic device showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the packaging with case for electronic device that form no part of the claimed design.

1 Claim, 6 Drawing Sheets
